(57) **CLAIM**

The ornamental design for a pole base, as shown and described.

DESCRIPTION

FIG. 1 is a top perspective view of a pole base showing my new design;

FIG. 2 is a right side view of the pole base, with the left, front, and back being a mirror image thereof;

FIG. 3 is a top view of the pole base;

FIG. 4 is a bottom view of the pole base; and,

FIG. 5 is a bottom perspective view of the pole base.

Each of the views of the right, left, front and back sides of the pole base are the same.
